(57) CLAIM

We claim the ornamental design for a finger sander, as shown and described.

DESCRIPTION

FIG. 1 is a top perspective view of a finger sander showing our new design;

FIG. 2 is a bottom perspective view thereof;

FIG. 3 is a top view thereof;

FIG. 4 is a front end view thereof;

FIG. 5 is a back end thereof;

FIG. 6 is a right side elevational view thereof, the left side being a minor image; and,

FIG. 7 is a bottom plan view thereof.

The broken lines in FIGS. 1-4 and 6 illustrate oval features that form no part of the claimed design.
